BEDDING PROTECTIVE DEVICE

Filed June 3, 1929

INVENTOR:
Albert L. Frank
BY *Pier L. Frank*
ATTORNEY

UNITED STATES PATENT OFFICE

ALBERT L. FRANK, OF SEATTLE, WASHINGTON, ASSIGNOR TO SEATTLE TENT & AWNING COMPANY, OF SEATTLE, WASHINGTON, A CORPORATION OF WASHINGTON

BEDDING PROTECTIVE DEVICE

Application filed June 3, 1929. Serial No. 367,944.

This invention relates to bedding protecting devices, for use, more especially, in bunk houses of logging camps, road crews, etc., for safe-guarding the bed-clothes from becoming unnecessarily soiled. Under such working conditions, much dirt and foreign material is conveyed by the men's clothing onto the bedding of the bunks, where the men spend a proportionately large part of their 10 idle time relaxing and resting themselves in their working clothes, and in consequence difficulty is had in keeping the bedding clean and sanitary.

The object of the present invention, generally stated, is to provide means adapted to be conveniently applied about a mattress and bed clothes of a bunk for the purpose of excluding dirt and moisture therefrom.

Another object is to provide a bed-protecting device which is adapted to be employed as a mattress sheath against rust deposition from the springs, and which will also accommodate the bedding of a bunk.

More specific objects and advantages of the invention will appear in the following description.

The invention consists in the novel construction, adaptation and combination of parts hereinafter described and claimed.

30 In the accompanying drawing,—

Figure 1 is a top plan view of a bedding protecting device constructed according to the present invention, the fly member being shown in its spread or extended position.

35 Fig. 2 is a plan view of the same, shown partly folded; and Fig. 3 is a perspective view showing the cover fully folded and illustrative of the position assumed when in use.

A cover for the bedding and mattress of a 40 bunk, according to the present invention, is formed, preferably, of a waterproof canvas, or other suitable light weight material.

Said cover is formed to provide a sheet which is capable of being folded along lines 45 4, 5, and 6, to provide a bottom flap 7, a fly member 8, and side flaps 9 and 10, disposed at opposite sides of said fly member 8, and arranged for depending relationship thereto.

More particularly, said cover is constructed of two rectangular sheets connected

longitudinally one with the other by a tongue 13 of the material disposed between the folding lines 4 and 5. The lateral edges 11 and 12 of flap 7 are turned or folded upon themselves to provide two-ply side marginal edges, 55 or reinforcements, extending the entire length of the sheet 7, and with three thicknesses at the tongue 13, that is to say—at opposite sides of the respective re-entrant angles 14 and 15. Thus it will be seen that the 60 tongue and the portion of the sheet 7 cooperating therewith, provides a two-ply, or double strength, foot wall 16 which, in turn, is further strengthened at the sides 11 and 12 as above explained. 65

17 represents a plurality of grommets provided within the laterally turned edges 11 and 12 to provide means readily engaged by lanyards (not shown) or other flexible device whereby the cover, as a whole, is secured to 70 the side rails of a bunk.

In use, the bottom flap 7 is secured above the springs of a bed and made fast thereto by means of the grommet-lanyard fastenings above referred to. The mattress and bedding 75 are placed above the bottom flap 7 to abut against the foot wall 16.

The fly 8 is then thrown over the made-up bed and may be utilized as a protection from the elements or as a security from dirt 80 brought upon the clothing of a person.

The construction and utility of the invention is believed apparent from the foregoing description.

What I claim, is,—

1. A protective covering for the mattress and the bedding of a bunk wherein a narrow portion is afforded for disposition beneath the mattress of the bunk, and a wider portion secured thereto for overlying the bedding and having side flaps depending from opposite edges to protect the sides of the mattress and the bedding, said wide and narrow portions consisting of respective approximate rectangular sheets of fabric, the former having a protruding tongue of less width than the narrow sheet extending from the end portion thereof and adapted to overlie said narrower sheet in affording a two-ply thickness transversely of the same, the lateral edges of said 95 100

last named sheet being folded and stitched upon itself to embrace the edges of said tongue in affording a three-ply thickness laterally of said tongue portion.

- 5 2. A protective covering for the mattress and bedding of a bunk consisting of an oblong member formed to provide two substantial rectangular sheets meeting on the approximate transverse median line of the member,
10 one of said sheets being of less width than the other to present re-entrant angles at both sides of the member, said member being also formed to provide a relatively inflexible portion extending from the transverse meeting
15 line of the sheets in the direction of the narrow end of the member a distance approximating the thickness of the mattress and bedding, the sheet of less width being adapted for introduction between the springs and the
20 mattress of the bunk, said relatively inflexible portion being adapted to extend across the vertical foot of the bunk, and the wide sheet being adapted to extend over the bedding of the bunk with the projecting lateral portions
25 thereof serving to cover the sides of the mattress and bedding.

3. A protective covering for the mattress and bedding of a bunk comprising an oblong member of relatively flexible material
30 formed to present re-entrant angles at both sides of the same offset from but adjacent the transverse median line of the member to provide two substantial rectangular sheets meeting on the transverse line of said angles with
35 one sheet being of less width but of greater length than the other sheet, such additional length of the narrower sheet approximating the thickness of the mattress and bedding of the bunk, the major portion of said narrower
40 sheet from its free end inwardly being introduced between the springs and mattress of the bunk with the inner portion of the same being turned up to overlie the vertical foot of the mattress and bedding, the sheet of
45 greater width being turned back over the bedding of the bunk with the extended lateral portions of the same serving to cover the sides of the mattress and bedding.

Signed at Seattle, Washington, this 24th
50 day of April, 1929.

ALBERT L. FRANK.
